CLAIM

The ornamental design for a combined mop bucket and wringer, as shown and described.

DESCRIPTION

FIG. 1 is a perspective view of a combined mop bucket and wringer according to my new design.

FIG. 2 is a top plan view of the combined mop bucket and wringer shown in FIG. 1;

FIG. 3 is a bottom plan view of the combined mop bucket and wringer shown in FIG. 1;

FIG. 4 is front elevation view of the combined mop bucket and wringer shown in FIG. 1;

FIG. 5 is a rear elevation view of the combined mop bucket and wringer shown in FIG. 1;

FIG. 6 is a right side elevation view of the combined mop bucket and wringer shown in FIG. 1; and,

FIG. 7 is left side elevation view of the combined mop bucket and wringer shown in FIG. 1.

The ornamental design which is claimed is shown in solid lines in the drawings. Any broken lines in the drawings are for illustrative purposes only and form no part of the claimed design.
